No. 11,393

September 2, 1879

UNITED STATES PATENT OFFICE.

BENJAMIN WEIAND, OF PHILADELPHIA, PENNSYLVANIA, ASSIGNOR TO
SCHNEIDER, STROHEIM & CO., OF NEW YORK, N. Y.

DESIGN FOR FURNITURE-COVERINGS.

Specification forming part of Design No. **11,393**, dated September 2, 1879; application filed June 24, 1879.
[Term of patent 3½ years.]

To all whom it may concern:

Be it known that I, BENJAMIN WEIAND, of the city of Philadelphia and State of Pennsylvania, have invented a new and original Design for Furniture-Coverings, of which the following is a full, clear, and exact description, reference being had to the accompanying photographic illustration, making part of this specification, in which—

A A are conventional basket-shaped figures, which are arranged in parallel rows, the baskets of one row alternating with the baskets of the adjoining rows. From the baskets rise twigs B, of which one extends toward the left-hand basket of the next row above, while the other twig has two branches, of which one branch extends vertically in the direction of the basket in the second row above, so as to fill up the space vertically above, the first basket, and the other branch toward the right-hand basket of the next row, so as to fill up the space between the first basket and the next adjoining basket on the right-hand side thereof. Smaller branch twigs extending from the left-hand twig, and also from the middle branch, fill up the space between the baskets and adjacent twigs.

The baskets have a square base, symmetrical sides, a surmounting top piece, and a cen-

tral ornament, while the twigs by which the space between the rows of baskets is filled up are formed of leaves, berries, and flowers that issue from the bent stems.

The repetition of baskets and twigs forms a pleasing design of apparently irregular, yet uniform, light, and elegant character.

Having thus described my invention, I claim as new and desire to secure by Letters Patent—

The design for a furniture-covering, composed of conventional baskets, arranged alternately in rows, and filling-twigs, of which one extends to the basket on the left-hand side and is provided with a small branch twig, while the other twig branches out into two parts, of which one part fills the space vertically above the basket, the other the space between the first basket and the next adjoining basket on the right-hand side of the former, substantially as shown and described.

In testimony that I claim the foregoing as my invention I have signed it this 17th day of June, 1879.

BENJ. WEIAND.
